UNITED STATES PATENT OFFICE.

KENNETH N. CRITCHFIELD, OF DETROIT, MICHIGAN.

HEEL FOR BOOTS OR SHOES.

1,369,166.

Specification of Letters Patent. Patented Feb. 22, 1921.

Application filed May 4, 1918. Serial No. 232,507.

To all whom it may concern:

Be it known that I, KENNETH N. CRITCHFIELD, a citizen of the United States, residing at Detroit, county of Wayne, State of Michigan, have invented a certain new and useful Improvement in Heels for Boots or Shoes, and declare the following to be a full, clear, and exact description of the same, such as will enable others skilled in the art 10 to which it pertains to make and use the same, reference being had to the accompanying drawings, which form a part of this specification.

This invention relates to heels for boots 15 or shoes, and an object of the invention is to provide a metal heel of the design required for any particular type of shoe, that is hollow in form and light in weight and is further to provide a heel that is serviceable 20 in character and of long life as compared to the usual wooden heels now manufactured. A further object is to provide a heel that is neat in appearance, and that may be securely fastened to the shoe without 25 liability of stripping it therefrom. An additional object of the invention is a metal heel adapted to support a leather or rubber base or tread portion to cushion the same, and a further novelty of the invention is in 30 the construction of the base of the heel providing a metal wearing plate formed integral with the heel and other features reside in the means of securing the leather heel cap to the base of the heel. These several 35 objects and novel features of the invention are shown in the accompanying drawings illustrating an embodiment of my invention in which—

Figure 1 is a side view thereof.

40 Fig. 2 is a plan view of the base of the heel.

Fig. 3 is a cross section taken on line $x-x$ of Fig. 1 and showing the mode of attaching the heel to a shoe.

45 Fig. 4 is a plan view of the heel.

The heel is preferably made of cast aluminum or lynite having comparatively thin walls and open at the upper side which is provided with an angular face 2 as shown. 50 This face may be varied in angle or shape to conform to the character and design of the shoe with which it is to be used.

As is shown in the drawings the heel 1 is 55 preferably hollow in form having an open upper end and closed at the lower or tread end. The upper end is provided with the tapped

holes 3 therein for securing the heel to the shoe. The preferred method of securing the heel to the shoe or boot is shown in cross section in Fig. 3, and for this purpose a top 60 metal plate 4 is utilized in the interior of the shoe apertured to receive the screws 5 threaded in the recesses 3 of the metal heel. The vamp 6 of the shoe is secured between the top plate and the face of the heel 1 and 65 by this arrangement the heel is securely and rigidly connected with the shoe. The shoe upper is indicated at 7 and is preferably turned beneath the vamp 6. The base 70 of the heel is closed at the bottom as shown with a thickness of metal greater than that of the side walls. The base is provided with an extending lip or lug 8 at the edge as shown particularly in Figs. 1 and 2, the purpose of which is to act as a wearing plate. 75 A leather or rubber tread member 9 of a thickness equal to the length of the projecting lug 8 of the base is secured to the bottom of the heel by means of a screw 10 passing through the leather or rubber heel cap 80 and threaded in the base of the heel 1 shown particularly in Fig. 1. The heel cap 9 is notched on one side to receive the wearing plate 8 and, as a further means of securing the leather cap to the base of the heel, I provide 85 a brass wire member 11 preferably U-shaped in form that is cast in the metal of the base having the two ends 12 projecting downward through the base as will be understood from the drawing. The two ends 12 are of 90 a length to extend through the heel cap and are swaged or headed at the end to act as a retainer for the leather tread. These several instrumentalities—namely, the wire member 11, screw 10, and wearing plate 8 95 serve to hold the heel cap in place and to prevent rotation thereof about the screw member and also prevent stripping of the tread from the heel.

The heel is preferably die-cast, which 100 process is well known, and by means of which the cost is reduced to a minimum in that the walls of the casting are formed with a very smooth surface and with threaded apertures for the screws thus reducing labor 105 cost to a minimum. It is further to be understood that the heel should be enameled or otherwise finished to conform to the color of the shoe with which it is to be used, and it is evident that a heel constructed as described is superior in appearance to and more serviceable in use than the usual type 110

of heel, and further that the mode of attaching to the shoe by binding the vamp between the top plate and the heel provides a heel that is practically impossible in ordinary use to strip from the shoe.

Having thus briefly described my invention, what I claim and desire to secure by Letters Patent of the United States is—

1. A heel for shoes consisting of a hollow cast metal body, open at the upper end and closed at the base, a leather tread having a notch on one side and said base having an integral portion extending into the notch terminating at the surface of the tread, said base having soft metal members cast in the body of the heel and extending through the said tread member to prevent displacement thereof.

2. A heel for shoes consisting of a hollow cast aluminum body, the heel being open at the upper end and closed at the tread end, a

tread of leather attached to the said tread end, and brass wire members cast in the said tread end providing means for securing the tread to the heel substantially as described. 25

3. A heel adapted to be attached to shoes consisting of a hollow cast aluminum body open at the upper end and shaped at the said end to correspond with the portion of the shoe to which it is to be attached, a 30 leather heel tap secured to the base or tread end having a notch in one side thereof, the base having a projecting portion terminating in a plane with the lower face of the tap providing a wearing plate, said base having a brass wire cast therein projecting from the base member and adapted to pass through the heel tap and headed over to secure the tap to the heel.

In testimony whereof I sign this specification.

KENNETH N. CRITCHFIELD
